UNITED STATES PATENT OFFICE.

LARKIN S. SAFFORD, OF KELSO, NORTH DAKOTA.

AUTOMATIC SINK-DOOR OPENER.

SPECIFICATION forming part of Letters Patent No. 650,422, dated May 29, 1900.

Application filed May 15, 1899. Serial No. 716,862. (No model.)

To all whom it may concern:

Be it known that I, LARKIN S. SAFFORD, a citizen of the United States, residing at Kelso, in the county of Traill and State of North

5 Dakota, have invented certain new and useful Improvements in Automatic Sink-Door Openers; and I do hereby declare the following to be a full, clear, and exact description of the invention, such as will enable others 10 skilled in the art to which it appertains to make and use the same.

My invention has for its object to provide a simple and efficient device for use in connection with sinks having swinging or otherwise movable doors, whereby the door will be 15 swung and held open whenever the catch pail or receptacle is nearly filled.

To the above end my invention consists of the novel devices and combinations of devices 20 hereinafter described, and defined in the claims.

In my prior application, filed September 12, 1898, and allowed February 20, 1899, which application bears Serial No. 690,734 and is entitled an "Automatic sink-door opener," the 25 sink-door was opened by means of a float device.

In my present invention I dispense with the float and so construct and poise the catch 30 pail or receptacle that the gravity of the water caught by the same will tilt the pail or receptacle when it has been nearly filled, and thus cause the pail to force open and hold open the door of the sink. This may be accomplished in several different ways, and in 35 the accompanying drawings I have given two illustrations.

In the accompanying drawings, like characters indicating like parts throughout the 40 several views, Figure 1 is a transverse vertical section through an ordinary sink having applied thereto one of my improved attachments for opening the door thereof. Fig. 2 is a horizontal section on the line $x^2 x^2$ of Fig. 45 1. Fig. 3 is a plan view of the so-called "tilting pail-support." Fig. 4 is a transverse vertical section taken on the line $x^4 x^4$ of Fig. 3. Fig. 5 is a transverse vertical section corresponding to Fig. 1, but illustrating a different 50 form of the attachment; and Fig. 6 is a rear elevation of the catch pail or receptacle employed in the illustration given in Fig. 5.

1 indicates the cabinet of an ordinary sink, the same being provided with the hinged door 2 and a sink-bowl 3, with depending drip- 55 pipe 4.

The catch pail or receptacle, which, it may be incidentally stated, is advisably constructed of thin metal, is indicated by the numeral 5 and is shown as provided with an ordinary bail 6, by means of which it may be readily carried. Within the pail is a vertical and transversely-extended partition 7, which terminates some little distance below the top of the pail and serves an important function, 65 which will be hereinafter noted. It may be here added that the partition 7 divides the pail into two compartments 7^a and 7^b. The pail is provided with a segmental cover 8 9, which nearly or quite covers the compartment 7^b, the section 8 being fixed to the pail and the section 9 being hinged thereto at 10. The segmental cover 8 9 prevents splashing or spilling of the water when the pail tilts, as 70 hereinafter described, and at the same time 75 direct access is given to the compartment 7^b when the hinged section 9 is raised. The hinged section 9 is a convenient and desirable, although not an indispensable, feature.

In the construction illustrated in Figs. 1 to 4, inclusive, a tilting pail-support is employed, this tilting pail-support in its preferred form comprising the skeleton bottom 11 and a block or weight 12, secured to one end thereof. On that side of the center of gravity of the support 11 12 and pail 5 which is opposite to the weight or block section 12 the bottom 11 is provided with the pair of transversely-extended parallel cleats 13, between which a single cleat 14 on the bottom of the sink 1 is 90 adapted to work as a fulcrum to the said pail-support. In the construction illustrated a transversely-extended strip 15, secured below the weight or block 12, limits the downward movement of that end of the support. Furthermore, as is shown, the inner face of the weight or block is hollowed out, as shown at 16, to receive the adjacent side of the pail or receptacle 5 and to properly locate the same on its support. 95

The operation of the device illustrated in Figs. 1 to 4, inclusive, is substantially as follows: The proper normal position of the catch-pail on the tilting support is indicated in 100

Figs. 1 and 2, by reference to which it will be seen that the compartment 7^a stands below the drip-pipe 4 and the outer edge of the pail stands very close to the inner surface of 5 the swinging door 2, this relative position being indicated in the said views by the full lines. The door 2 may be ordinarily or normally held closed either by gravity, a light spring, or by a slight friction, it of course 10 being necessary that the door be free to swing open when a slight force is applied thereto. It will be noted that the center of the fulcrum-cleat 14 extends to one side of the vertical axis of the pail and lies under the compartment 7^a thereof. In other words, more 15 than one-half of the pail stands between the vertical planes of the axis of the pail and of the door 2. The soiled water discharged through the pipe 4 will fall into the compartment 20 7^a and will have a tendency to hold the pail and the tilting support in their normal positions until after the water has overrun the top of the partition 7 and nearly filled the compartment 7^b, at which time the center of 25 gravity of the water in the said pail having been shifted outward or toward the door 2 will overcome the gravity of the weight or block 16 and will tilt the pail and its tilting support into the positions indicated by dotted lines in Fig. 1, and thereby engaging the 30 said door and forcing the same into its opened position, also as indicated in said Fig. 1. When the door has thus been swung open, it will of course indicate that the pail has been 35 nearly, although not quite, filled and needs emptying.

In the construction illustrated in Figs. 5 and 6 a grooved cleat 17 is secured to the bottom of the sink and the pail is provided on its 40 bottom with a pair of depending fulcrum-lugs 18 or ears that work in the groove of the said cleat 17. The heavy handle 19 on the inner side of the pail acts as a weight to assist in normally holding the pail, as indicated by full 45 lines in Fig. 5. When in its normal position, the inner edge of the pail is supported by a screw 20, which, as shown, is screwed into the bottom of the sink and is provided with a removable cap 21. In this construction the 50 fulcrum-lugs 18 are so located with respect to the center of gravity of the pail—the weight

of the handle 19 of course affecting this center of gravity—that the pail when empty will stand in its normal position, and when the compartment 7^b is nearly filled to the top of 55 the partition 7 said pail will tilt outward against the sink-door and force the same open in very much the same manner as will the device illustrated in Figs. 1 to 4, inclusive. The point or time with reference to the fullness of the pail may be varied considerably by the adjustment of the supporting-screw 20, and it will be understood that I do not limit myself to this specific means of setting or adjusting the pail. 60 65

What I claim, and desire to secure by Letters Patent of the United States, is as follows:

1. The combination with a sink involving a bowl and a cabinet or case having a movable door, of a catch pail or receptacle within 70 said cabinet, mounted to tilt over a fulcrum which is so located with respect to the center of gravity of said pail that said pail will stand in one position when empty, and when nearly filled will tilt, and by its tilting movement 75 open the said sink-door, substantially as described.

2. The combination with a sink involving a bowl and a cabinet having a movable door, of a catch pail or receptacle within the cabinet mounted to tilt over a fulcrum which is so located with respect to the center of gravity of said pail that it will stand in one position when empty, and when nearly filled will tilt into a position to engage and open said 80 door, substantially as described.

3. The combination with a sink involving a bowl and a cabinet having a movable door, of a catch pail or receptacle having a transverse partition terminating below the top 90 thereof, said pail being mounted to tilt over a fulcrum which is so located with respect to its center of gravity that said pail will stand in one position when empty and when nearly filled will tilt to engage and open said door, 95 substantially as described.

In testimony whereof I affix my signature in presence of two witnesses.

LARKIN S. SAFFORD.
